UNITED STATES PATENT OFFICE.

EDWARD C. GOEDDE, OF CHICAGO, ILLINOIS.

PHONOGRAPH-RECORD HOLDER.

1,393,771.

Specification of Letters Patent. Patented Oct. 18, 1921.

Application filed June 20, 1919. Serial No. 305,572.

To all whom it may concern:

Be it known that I, EDWARD C. GOEDDE, a citizen of the United States, and a resident of Chicago, Cook county, and State of Illinois, have invented certain new and useful Improvements in Phonograph-Record Holders, of which the following is a specification.

My invention relates generally to improvements in means for holding phonograph records and relates particularly to means for holding and storing disk records.

Phonograph records are made of material which is easily broken or scratched, thereby destroying or injuring same. Many of the records produced by well known artists are quite expensive and the slightest injury to the reproductive surface thereof, to all artistic purposes, destroys the record.

For the above reasons, and others, it is necessary to hold the records in separated condition so that there shall be no danger of scratching or marring the surface of the record when it is removed from its stored position. Inasmuch as the average owner of a phonograph has a large number of records it is also quite necessary to provide some means so that it shall be possible immediately to find and remove the desired record, thereby avoiding the necessity of examining a number of records with the consequent liability of breaking or marring the surfaces thereof.

The most convenient place for the storing of phonograph records is within the phonograph cabinet, which is usually provided with a space for that purpose, but this space is relatively small and places a limitation upon the number of records that can be accommodated therein.

It has been proposed heretofore to provide holders of one kind or another suitable for placement in the phonograph cabinet but they have embodied certain objectionable features such, for example, as unduly limiting the capacity of the cabinet; being easily broken; likely to injure the records, or being of such an expensive construction as to be practically prohibitive.

The general object of my invention is to provide a record holder in which it shall be possible to store a large number of records within a relatively small space.

Another object of my invention is to provide means whereby it shall be possible to hold a large number of records in such form

that the desired record can be immediately found and conveniently removed, and in which the storage, removal and insertion of the records can be accomplished without danger of breaking or injuring the reproductive surfaces thereof.

Again it is an object of my invention to provide a record holder which shall be of such construction that it can be manufactured cheaply; which shall be easily operable, durable and of such character that it can be placed, if desired, within the usual storage space of a cabinet phonograph.

My invention consists generally in the form, construction, arrangement and association of the parts whereby the above named objects, together with others that will appear hereinafter, are attainable, and my invention will be more readily understood by reference to the accompanying drawings which illustrate what I consider to be the best embodiments thereof at the present time.

In said drawings Figure 1, is a plan view of a holder embodying my invention. Fig. 2, is a front elevation thereof. Fig. 3, is a detailed sectional view substantially on the line 3-3 of Fig. 1. Fig. 4, is a detailed sectional view similar to Fig. 3, but illustrating a modified form of my invention. Fig. 5, is a sectional view substantially on the line 5-5 of Fig. 2. Fig. 6, is a perspective view of one of the holder members of that form of my invention shown in Figs. 1, 2, 3, and 5; and Fig. 7, is a perspective view of one of the holder members of that form of my invention shown in Fig. 4.

The holder herein shown comprises a frame composed of spaced front and rear bottom members, 1 and 2, respectively, upon which are secured vertical side members, 3 and 4, which side members hold the bottom members, 1 and 2, in proper spaced relation. Secured to the rear edge 5, of the rear bottom member 2, and upstanding therefrom is a back member 6, to the upper edge 7, of which is attached a forwardly extending member 8. The upper edge 7, in the present instance, is beveled so that the member 8 occupies an inclined position, the purpose of which will shortly appear.

As is well shown in Fig. 1, member 8, is secured to the rear member 6, by means of screws 9, and to the side members 3 and 4, by screws 10 and 11, respectively. In

this manner a very rigid frame is provided and yet one which is light in weight and very easily and cheaply made.

- The frame work above described serves to
- 5 house or contain a large number of record holder members 12, which are alike in every respect except that they are preferably provided with tongue or finger gripping portions 12', 12'' and 12''', of differing lengths,
  - 10 and preferably also differently disposed, more conveniently to enable the designation of the records contained therein and the removal of the desired record. As a matter of convenience I shall hereinafter refer
  - 15 to the members 12 as individual record supports and to the device as a whole, as a record holder. That form of individual record support disclosed in Figs. 1, 2, 3, 5 and 6, is composed of a relatively thin elongated
  - 20 slab from one side face, of which projects a tongue 13, and in the other side face of which is formed a groove 14, corresponding in depth and width to the depth and width of the tongue portion 13. Thus it becomes
  - 25 possible to associate two of the individual record supports 12, in intimate side by side relation, the tongue 13, of one member being accommodated within and co-acting with the groove 14, of the next adjacent member.
  - 30 Each individual record support is provided with a somewhat similar circular or curved cut-away portion indicated at 15, the depth of which is substantially equivalent to the thickness of the usual disk phonograph record. This groove terminates just above the bottom of the individual holder thus providing a ledge 16, upon which the bottom of the record would rest if it were
  - 35 of such size as not to engage the upper curved portions of the groove and rest thereon. As a matter of fact I prefer so to make the curve 15, that the bottom of the record shall always be quite close to the ledge 16, for it will be noted that in forming the
  - 40 groove for the reception of the record the material is completely cut away as at 17, being that part of the individual record support where the groove 14, meets the record receiving groove 15. By this construction,
  - 45 the tongue 13, in a sense forms a strap between the central portion 18, of the upper part of the individual holder and the central lower part 19, and when a phonograph record is placed in the holder any tendency
  - 50 of it to cant is prevented by the strap-like or binding action of the tongue 13.

The interfitting tongue and groove construction provides a slide which is firm and yet which can be readily withdrawn

60 and replaced.

I prefer also to bevel the upper rear end of the holder, as shown at 20, so that when it is returned to its storage position, it will wedge into place under the inclined cross members 8, thus serving to hold it in place

with sufficient friction to require a positive pull for its release.

In order that the slide shall not accidentally be entirely removed from the frame I prefer to provide stop means which in the present instance assumes the form of a pin 21, secured in the bottom of each individual record support and which is so positioned that it permits withdrawal of the support a distance sufficient to enable convenient removal of the record carried by the slide or record support but which prevents complete removal by engagement with the face 22 of the front frame member 1.

By the novel construction disclosed, it becomes possible to store a very large number of records within a relatively small space, because the tongue or guide not only forms part of the record receiving slot but also by engagement with the corresponding groove in the next adjacent slide or record support forms a suitable guide, therefor. This construction also serves to prevent the rocking or tipping of the holder when it is pulled to its outermost position, as necessary for the purpose of extracting the record contained in that particular individual holder.

The tongue or finger gripping portions 12', 12'' and 12''' are also preferably provided with index numbers as indicated at 23, to designate the record contained therein, and by making the finger gripping portions 12', 12'', and 12''' of different lengths the viewing of the designating characters is enhanced. The convenient gripping of the finger portions is further aided by the staggered relation of the parts as is well shown in Fig. 1.

That form of my invention shown in Figs. 4 and 7, differs in some respects from the one heretofore described but inasmuch as the frame member of the record holder is the same it will not be again described. The individual record supporting member in this form is composed of a slab-like elongated member, in one face of which a cut-away or depressed portion 24, is provided for the accommodation of the lower edge portions of a disk record. The depth of this recess *i. e.* from the face 25 of the holder to the face of the bottom of the recess is approximately the same as the thickness of a standard disk record. As is well shown in Fig. 4, a large number of the record supporting members 26, are associated in side by side relation and when so associated form a plurality of vertical grooves 27. When the records are placed in these grooves one face of the record is in engagement with the face of the groove or recess 24, and the other is in contact with or restricted by the face 28, of the adjacent slide.

By this construction the same number of records can be accommodated within a given

space as in that form of my invention first described, but the desirable strapping of the record in place and the guiding of the individual record support in its to and fro movement is not found. In this form of my invention as in the first form I prefer also to provide stop means as indicated at 29.

Both forms of my invention, however, can be easily manufactured from standard materials and if produced in wood, by usual mill machinery.

Inasmuch as this invention will disclose to others modified constructions whereby the substantial objects of my invention may be attained, I do not wish to be limited to the herein described construction except only as may be necessary by limitation in the hereunto appended claims.

I claim:

1. A record holder embodying therein a frame, a plurality of individual record supports mounted in side by side relation therein, each record support having a record receiving groove formed by a depression in one side face thereof, and the adjacent record support having a side face which directly abuts that side face of the first mentioned record support that contains the groove and bounds, at least in part, said record receiving groove.

2. A record holder embodying therein a frame, a plurality of individual record supports mounted in side by side relation therein, each of said record supports having a raised portion on one side and a groove upon the other, the raised part of one record support entering the groove of the adjacent record support and each of said record supports having a disk record receiving groove at least part of which is bounded by the face of the adjacent record support.

3. A record holder embodying therein a

frame, a plurality of individual record supports mounted in side by side relation therein, each having a disk record receiving groove therein, at least part of which is bounded by the face of the adjacent record support and each of said record supports having a centrally arranged tongue on one side and a centrally arranged groove of like size upon the other, the tongue of one holder entering the groove of the adjacent record support.

4. A record holder embodying therein a frame, a plurality of individual record supports mounted in side by side relation therein for horizontal sliding movement and each having a record receiving groove therein at least part of which is bounded by the face of the adjacent record support, and means for limiting the inward movement of said record supports, said means including a beveled portion at one end of the record support and a co-acting inclined portion on the frame.

5. A record holder embodying therein a frame, a plurality of individual record supports mounted in side by side relation therein, each of said record supports having a raised portion on one side and a groove upon the other, the raised part of one record support entering the groove of the adjacent record support and each having a disk record receiving groove at least part of which is bounded by the face of the adjacent record support, together with means limiting the inward movement of the said record supports, and resisting the outward movement thereof, said means including a beveled portion at one end of each record support, and a co-acting inclined portion on the frame.

In testimony whereof, I have hereunto set my hand, this 21st day of May, 1919.

EDWARD C. GOEDDE.
